UNITED STATES PATENT OFFICE.

ALEXANDER M. KERR, OF DETROIT, MICHIGAN, ASSIGNOR OF THREE-FOURTHS TO THE FULTON IRON AND ENGINE WORKS, OF SAME PLACE.

LOCK FOR HOISTING-TACKLE.

SPECIFICATION forming part of Letters Patent No. 389,155, dated September 4, 1888.

Application filed May 3, 1888. Serial No. 272,731. (No model.)

To all whom it may concern:

Be it known that I, ALEXANDER M. KERR, of Detroit, in the county of Wayne and State of Michigan, have invented a new and useful 5 Improvement in Locks for Hoisting-Tackle, of which the following is a specification.

My invention consists in an improved lock for hoisting-tackle, hereinafter fully described and claimed.

10 Figure 1 is an elevation of the tackle complete. Figs. 2 and 3 are side views of the upper and lower pulleys. Fig. 4 is a top plan view of the wedge, and Fig. 5 a side elevation of the wedge.

15 A represents a hook, the shank of which is fastened to a pin, B, which passes through the cheek-plates C of a pulley and serves to support them.

20 E and H represent two sheaves journaled on shafts F and G, set in the cheek-plates C; but instead of being placed side by side, as usual, they are placed one behind the other, as clearly shown in Fig. 1.

25 If the pulley is to have more than two sheaves, all but one may be placed side by side, as in the ordinary construction, (shown in the lower pulley, Fig. 3,) with one sheave placed back of one of the others, so that no matter how many sheaves there are in the upper block 30 two of them will occupy the relations of the sheaves E and H.

35 T and R represent the sheaves of a double pulley of the ordinary construction journaled on the shaft Q, and provided with a stirrup, P, and foot S, for attachment to the load.

40 N represents a wedge-shaped piece of metal adapted to play between the adjacent faces of the sheaves E and H, and in its descent to wedge firmly between the rope on said sheaves.

45 O represents a shaft journaled in the cheek-plates C, and carrying between those plates a cam, W, which engages with wedge N, so that by rocking said shaft the wedge N can be lifted away from the sheaves.

50 D represents a lever secured to the end of shaft O, by means of which, through a chain or rope attached thereto, the shaft O can be rotated.

The rope or chain is to be so rove that the sheaves E H will always turn in opposite 50 directions, and this may be done as follows: The running end of the rope I passes above sheave H and then down, as shown at J, under sheave T, up, as shown at K, over sheave E, down, as shown at L, under sheave R, and then up, as shown at M, to its point of attachment to its cheek-plates C. This point of attachment is shown at one side in the drawings, in order to enable the different lengths of rope 55 to be shown without conflict. It will be seen that whether the lower pulley is being raised or lowered the sheaves E H always turn in opposite directions, either toward or away from each other, and the lengths of rope J and K will always run in the same direction, and 60 will run downward when the lower pulley is descending. By permitting the wedge N to descend when the sheaves E H are turning toward each other and the lengths of rope J K are running downward, it is evident that the 65 wedge N will be drawn between said ropes and lock them, so as to hold the ropes stationary and arrest the lower pulley at any desired point in its descent. When the ropes J K run upward, which occurs in raising the lower 70 pulley, the motion of the ropes lifts the wedge N, so that it does not interfere with their operation, and when it is desired to lower the lower pulley the wedge N is held up out of contact with the ropes J K by depressing the 75 right-hand end of the lever D, Fig. 1, which causes the cam W to lift the wedge N away from the ropes and permits the sheaves to rotate freely.

What I claim as my invention, and desire to 80 secure by Letters Patent, is—

1. The combination, with a pulley-block having two sheaves arranged one behind the other to turn in opposite directions, of a vertically-movable wedge suspended between the 85 two sheaves, and having opposite inclined surfaces adapted to wedge between the opposite portions of a rope passing around the respective sheaves, substantially as described.

2. The combination, with a pulley-block 90 having two sheaves arranged one behind the

other to turn in opposite directions, of a vertically movable wedge suspended between the two sheaves and having its opposite inclined surfaces adapted to wedge between the 5 opposite portions of a rope passing around the respective sheaves, a rocking shaft journaled on the sheave frame and having a cam

engaging the wedge, and a lever, D, for rocking the cam-shaft, substantially as described.

ALEXANDER M. KERR.
